UNITED STATES PATENT OFFICE.

ROBERT P. BEATTY, OF CLEVELAND, OHIO, ASSIGNOR TO THE BEATTY STAMPING CO., OF CLEVELAND, OHIO, A CORPORATION OF OHIO.

GARMENT-HANGER.

No. 893,298.

Specification of Letters Patent.

Patented July 14, 1908.

Application filed January 30, 1907. Serial No. 354,809.

To all whom it may concern:

Be it known that I, ROBERT P. BEATTY, a citizen of the United States, resident of Cleveland, county of Cuyahoga, and State of Ohio, have invented a new and useful Improvement in Garment-Hangers, of which the following is a specification, the principle of the invention being herein explained and the best mode in which I have contemplated 10 applying that principle so as to distinguish it from other inventions.

My invention relates to garment hangers, and particularly to trousers-hangers in which the trousers are suspended from the 15 top thereof.

Said invention has for its object the provision of a hanger of the above-mentioned class, which shall be economical in construction, simple in operation, and will present as 20 little obstruction as possible when in use.

Said invention further consists in certain improvements upon the construction shown, described and claimed in United States Patent No. 780,091, issued January 17, 1905, to 25 Charles J. Dahlgren. Such improvements are hereinafter fully described and particularly set forth in the claims embodied in this application.

The annexed drawing and the following 30 description set forth in detail certain mechanism embodying the invention, such disclosed means, however, constituting but one of various mechanical forms in which the principle of the invention may be used.

In said annexed drawing: Figure 1 represents a side elevation of a trousers-hanger embodying my invention showing in dotted outline the upper portion of a pair of trousers in the position which it occupies when supported by the hanger. Fig. 2 represents an 40 end view of the same looking in the direction indicated by the arrow in Fig. 1, and Fig. 3 represents a perspective broken view of the angularly-projecting adjustable member.

Referring to Fig. 1, A is a straight rod of steel, of suitable thickness, which forms the supporting-bar of the hanger. Slidably mounted upon said bar is a wire hook B which is adapted to suspend the bar in a horizontal position, such hook being therefor adjustable and permitting the hanger to be properly balanced. At or near the front end of the bar is mounted a gripping spring-clip C of any well-known construction capable of

securely gripping and holding one end of the 55 upper portion of a pair of trousers. Said clip is preferably fixed relatively to the longitudinal direction of the bar but mounted so as to permit of its rotation about the bar's axis.

Upon the rearward portion of the bar is 60 slidably mounted a member D, this latter member comprising a base-member d and a member d' secured thereto and projecting angularly therefrom with reference to the 65 bar A. Member d' is made flexible and is preferably formed of a loop of spring-steel wire whose open end is inserted and fixed in two holes d³ d³ bored in the lateral portion of the base-member d, as shown in Fig. 3. Bar 70 A passes through a bore d⁴ formed in base member D, such bore being made a trifle larger in diameter than the diameter of bar A. The member D is furthermore provided with a member d² which forms a part of or is 75 fixed to the same, forming two lateral ears constituting a finger member, by means of which the member D may be readily pushed back, as will hereinafter appear.

In applying the above-described device, 80 the front upper-portion of the trousers is secured by the clip C as shown. Member D is then drawn forwardly along the bar until the flexible portion d' is capable of being inserted inside the trousers. Said member D, 85 by means of ears d² d², is then adjusted by being pushed back until it comes in contact with the rear portion of the trousers and with sufficient strength to stretch the fabric smoothly and flex the member d'. Such 90 action causes the base-member d to bite the bar and maintain the position given it. The flexed member d' maintains a constant pressure upon the inside of the rear of the trousers and holds the latter continuously in proper 95 position.

In the event that it is desirable to use the above-described hanger for suspending a pair of trousers from the bottom, a second 100 clip (shown in dotted lines) may be slidably mounted upon the bar for gripping, in conjunction with the clip B, the fabric of their lower end, as will be readily understood.

Other modes of applying the principle of my invention may be employed instead of 105 the one explained, change being made as regards the mechanism herein disclosed, provided the means stated by any one of the

following claims or the equivalent of such stated means be employed.

I therefore particularly point out and distinctly claim as my invention:—

- 5 1. In a trousers-hanger, the combination of a supporting-bar; a clip mounted at or near one end of the latter; and a member mounted upon and adjustable along said bar; said adjustable member comprising a base-member having laterally projecting ears forming a finger-portion, and a member secured to said base-member and consisting of a loop of resilient wire projecting angularly with reference to the bar; such loop having its open end secured to said base-member.
- 10 10. In a trousers-hanger, the combination of a supporting-bar; a clip mounted at one
- 15 15. In a trousers-hanger, the combination of a supporting-bar; a clip mounted at one

end of the latter; and a member mounted upon and adjustable along said bar; said adjustable member comprising a base-member having laterally projecting ears forming a finger-portion, and a member secured to said base-member and consisting of a loop of resilient wire projecting angularly with reference to the bar; such loop having its open end secured to said base-member.

Signed by me this 28th day of January 1907.

ROBERT P. BEATTY.
